UNITED STATES PATENT OFFICE.

MARTIN M. PLANK, OF GOTHENBURG, NEBRASKA.

ADJUSTABLE SUPPORT FOR GRAIN-CONVEYERS OF THRESHING-MACHINES.

1,318,585.

Specification of Letters Patent.

Patented Oct. 14, 1919.

Application filed May 31, 1918. Serial No. 237,584.

To all whom it may concern:

Be it known that I, MARTIN M. PLANK, a citizen of the United States, and a resident of Gothenburg, in the county of Dawson 5 and State of Nebraska, have invented certain new and useful Improvements in Adjustable Supports for Grain-Conveyers of Threshing-Machines, of which the following is a specification.

10 This invention relates to grain threshing machines or separators, and an object of the invention is to provide an attachment for the grain conveyer of a threshing machine or grain separator which is adjustable and 15 will hold the horizontal pivotally or swingably mounted conveyer in various adjusted positions, preventing accidental movement of this conveyer, under various conditions, such as under a heavy wind, or by being 20 engaged by some article during the grain threshing operation.

More specifically, this invention comprehends the provision of a toothed bar which is pivotally and adjustably supported by 25 one of the vertical sections of the grain conveyer and is adjustably received through a suitable socket member carried by the swingable conveyer section and to provide a pivotally mounted spring controlled catch or 30 latch lever for engagement in any one of the recesses formed in the toothed bar for holding this bar against accidental movement and consequently holding the swingable conveyer section against accidental move- 35 ment.

Other objects of the invention will appear in the following detailed description, taken in connection with the accompanying drawings, forming a part of this specification, 40 and in which drawings:

Figure 1 is a side elevation of a fragment of a grain thresher showing the improved support attached to the grain conveyer thereof.

45 Fig. 2 is a top plan of the attachment showing the same applied to the grain conveyer.

Fig. 3 is a view illustrating in perspective, the support which is connected to one of the 50 vertical conveyers and to which the support bar is adjustably connected.

Fig. 4 is an enlarged fragmentary section of a part of the support, showing the major portion of the support in section.

55 Fig. 5 is a fragmentary side elevation of

the conveyer support illustrating the socket member.

Fig. 6 is a section on the line 6—6 of Fig. 5.

Referring more particularly to the drawings, A designates a grain threshing machine or separator of the ordinary construction, now commonly in use which carries a grain conveyer structure comprising the vertical conveyer B and the swingable conveyer section C which receives the grain 60 from the upper delivery ends of the vertical stationary conveyers B and delivers it to a wagon, sack or bin as desired. The improved support or attachment, comprising this invention is generically indicated by the 65 numeral 1 and is carried by one of the vertical conveyer sections B and connected to the swingable section C for holding this section against accidental swinging movement. 70

The supporting attachment 1 comprises a split ring structure 2 which is clamped upon one of the vertical sections B, in the usual manner of clamping split rings upon objects and it has a pair of diverging arms 80 3 and 4 formed thereon which extend outwardly from their attached or connected portions and are twisted intermediate their ends as shown at 5, to position their outer ends in horizontal planes. Straps 6 are attached to the outer horizontal ends of the arms 3 and 4 and are spaced therefrom for receiving therebetween the flat horizontal end 7 of the toothed supporting bar 8. The horizontal end 7 and the horizontal outer 85 ends of the arms 3 and 4 and the straps 6 are provided with openings adapted to align and receive a pin 9 for connecting the bar 8 to one of the arms 3 and 4. The bar 8 extends outwardly and is inserted through a 90 socket member 10 carried by the conveyer section C. The socket member 10 comprises a standard 11 having a lateral enlargement 12 formed upon one side of the same which is provided with an opening 13 through 95 which the toothed bar 8 extends. The standard 11 has a split ring 14 formed upon its lower end which is securely clamped about the conveyer section C by the bolt structure 15, for supporting the socket member upon the swingable conveyer section C 100 outwardly of the support of this structure.

The upper end of the standard 11 is bifurcated, and a latch lever 16 is pivotally connected to and positioned between the arms 110

formed by the bifurcating of the upper end of the standard. Spiral springs 17 and 18 are connected at their upper ends to a wire 19 which extends over the upper edge of the 5 latch lever 16, being held against longitudinal movement therealong by engaging in a notch 20 formed in the upper edge of the lever. The lower ends of the springs 17 and 18 are connected by a length 21 of the wire 10 of which they are formed and this length extends across the under surface of the enlargement 12 of the standard and engages in a notch 22 formed therein. The springs 17 and 18, being contractile springs hold the 15 end 23 of the lever downwardly and engagement in any one of the notches 24 formed in the upper edge of the bar 8, to hold this bar against accidental movement and consequently support the conveyer section C 20 against accidental movement upon its pivot or swiveled support. An operating rope or cable 25 is connected to the upper end of the lever 16, and passes over a supporting or guiding pulley 26 which is supported by a 25 suitable bracket 27. The bracket 27 may be attached to one of the depending ears of the split ring 14. The operating cord or cable 25 extends over the top of the thresher or separator, or along one side of the same to 30 any desired position where it may be conveniently reached and operated by an operator for controlling the movement of the conveyer section C.

The standard structure 11 is formed of an 35 upper section 28 and a lower section 29 which lower section has the split ring 14 formed thereupon and is also provided with an upstanding pin or spindle 30. The spindle or pin 30 rotatably engages in a recess 40 31 formed in the under surface of the section 28 of the standard 11 to connect the upper section 28 to the lower section 29 so as to permit rotary movement of the upper section upon the pin 30 as an axis which movement is necessary, to permit adjusting 45 swinging movement of the conveyer section C.

When the conveyer section C is to be supported in an extended position outwardly of 50 the separator body, the notched arm 8 is connected to the arm 4 of the split ring structure 2 but when it is desired to extend the conveyer section 3 over or across the top of the separator A, this arm 8 is connected 55 to the arm 3 of the split ring structure.

By providing a plurality of notches or recesses 24 in the upper edge of the bar 8, the conveyer section C may be held at any desired adjusted position within the limit of 60 its pivotal or swinging movement within the limit permitted by the connection of the arm 8 to either of the arms 3 or 4.

The ordinary or usual brace structure

generically indicated by the letter D is also connected to the conveyer section C for supporting the conveyer section in its proper adjustment as to elevation. 65

Having fully described the invention, what is claimed is:

1. The combination with a grain conveyer 70 for separators embodying a stationary section and a swingable section, of a pair of oppositely extending arms carried by the stationary section, a bar adapted for pivotal attachment to the outer ends of either of 75 said arms and provided with notches in its upper edge, a socket member rotatably supported by said swingable section and provided with an opening for receiving said bar therethrough, said socket member provided 80 with a recess having communication with said opening, a locking lever pivotally carried by said socket member and engaging through said recess and in any one of the notches in said bar. 85

2. The combination with a grain conveyer 90 for separators embodying a stationary section and a swingable section, of a pair of oppositely extending arms carried by the stationary section, a bar adapted for pivotal 95 attachment to the outer ends of either of said arms and provided with notches in its upper edge, a socket member rotatably supported by said swingable section and provided with an opening for receiving said bar therethrough, said socket member provided with a recess having communication with said opening, a locking lever pivotally carried by said socket member and engaging through said recess and in any one of the notches in said bar, said lever provided with a notch in its upper edge, a wire engaging in said notch, and a contractile spring connected to the ends of said wire for urging 100 said lever into the recess. 105

3. The combination with a grain conveyer 110 for separators embodying a stationary section and a swingable section, of a pair of oppositely extending arms carried by said rigid section, a bar adapted for pivotal attachment to the outer end of either of said arms and provided with notches in its upper edge, and a member attached to said swingable section, a socket member rotatably supported by said attaching member and provided 115 with an opening for receiving said bar therethrough, said socket member provided with a recess having communication with said opening, a locking lever pivotally carried by said socket member and engaging through 120 said recess and in any one of the notches in said bar, and a brace pivotally connected to said attaching member and to said stationary section. 110

MARTIN M. PLANK.
